UNITED STATES PATENT OFFICE.

ALBERT PICK, OF CHICAGO, ILLINOIS.

DESIGN FOR A WINE-GLASS.

SPECIFICATION forming part of Design No. 35,363, dated December 3, 1901.

Application filed October 30, 1901. Serial No. 80,575. Term of patent 7 years.

To all whom it may concern:

Be it known that I, ALBERT PICK, a citizen of the United States, residing at Chicago, in the county of Cook and State of Illinois, have 5 invented and produced a certain new and novel Design for a Wine-Glass; and I do hereby declare the following to be a full, clear, and exact description of the same.

My invention relates to a novel design for a wine-glass, the object being to provide a new and ornamental glass of this character.

The accompanying drawing shows a wine-glass embodying my design.

My invention consists in a wine-glass having a base, stem, and bowl, the latter being 5 supported upon the upright nude figure of a woman standing upon the base and resting

almost entirely upon one foot, the other foot resting only upon the toes. The head is tipped slightly to one side and the arms are 20 upraised, the hands being hidden behind the head. The bowl rests upon the head and fore-arms.

This design is very ornamental and effective and is very pleasing to the eye. 25

I claim as my invention—

The design for a wine-glass, substantially as shown and described.

In testimony whereof I affix my signature in presence of two witnesses.

ALBERT PICK.
